UNITED STATES PATENT OFFICE.

ARTHUR J. CULP, OF CLANTON, ALABAMA.

EXHAUST TRAP.

Application filed May 23, 1925. Serial No. 32,365.

This invention relates to the exhaust trap forming the subject matter of my U. S. Letters Patent 1,514,441, granted November 4, 1924, and has for one of its objects to 5 improve and simplify the general construction of said trap to the end that its cost of manufacture will be reduced to the minimum.

The foregoing and other objects are attained by the construction, combination and arrangement of parts hereinafter fully described and claimed, and illustrated in the accompanying drawings, wherein:

Figure 1 is a sectional view taken on a 15 vertical plane extending longitudinally and centrally through an exhaust trap constructed in accordance with the present invention and adapted for use in connection with a single cylinder hydro-carbon engine,

20 Figure 2 is a transverse sectional view of the exhaust trap, the section being taken on the plane indicated by the line 2—2 of Figure, 1,

25 Figure 3 is a detail view in elevation of the valve mechanism of the exhaust trap,

Figure 4 is a sectional view taken on a 30 vertical plane extending longitudinally and centrally through the exhaust trap adapted for use in connection with a multiple cylinder hydro-carbon engine.

Figure 5 is a view illustrating the application of the multiple trap to a hydro-carbon engine, and

35 Figure 6 is a detail sectional view taken on the plane indicated by the line 6—6 of Figure 5.

Corresponding and like parts are referred to in the following description, and designated in the several views of the accompanying drawings, by similar reference characters.

The exhaust trap comprises a cylinder or drum 1 made of sheet metal and provided at its ends with outwardly directed annular 45 flanges 2 and 3. A head plate 4 is secured to the flange 2 by rivets 5, and a head plate 6 is secured to the flange 3 by rivets 7, the former plate being provided with a central opening 8 and the latter with a central opening 9. An intake tube 10 passes 50 into the cylinder 1 through the opening 8, and has its outer end screw threaded as indicated at 11 in order to permit it to be coupled to a pipe leading from the exhaust 55 port of a single cylinder hydro-carbon engine. The intake tube 10 is secured in place

by a cast iron collar 12 with which it has threaded connection and which is attached to the head plate 4 by cap screws 13.

A baffle tube 14 having a closed end 15 and an open end 16, is arranged within the cylinder 1 about the intake tube 10 with its end wall 15 in spaced relation to the inner or discharge end of said intake tube. The baffle tube 14 is provided at its open end 16 with a conical extension 17 provided with openings 18 and constituting a baffle plate. A hollow cylindrical element 19 extends from the larger end of the baffle plate 17 and contacts with the inner surface of the cylinder 1. The outer end of the cylindrical extension 19 contacts with the head plate 4, and said extension constitutes a support for the baffle tube 14 and baffle plate 17 and is secured to the cylinder 1 by rivets 20. 60 The baffle tube 14 and baffle plate 17 separate the cylinder 1 into chambers 21, 22, and 23. The chamber 21 is the smallest, the chamber 23 the largest, and the chamber 22 is larger than the chamber 21 and 65 smaller than the chamber 23. The chambers 21 and 22 are in communication through the open end 16 of the baffle tube 14, and the chambers 22 and 23 are in communication through the openings 18. The exhaust passing out of the discharge end of the intake tube 10 passes first into the chamber 21, then into the chamber 22 and thence into the chamber 23 from whence it passes out of the trap through the opening 9.

70 A plate 24 is secured to the head plate 6 by cap screws 25, and is provided with an opening registering with the opening 9 and having its wall tapered to provide a valve seat 26. A valve 27 provided with a stem 28 passing through an opening 29 in a guide and support 30, is yieldingly held against the seat 26 by a spring 31 which is mounted on the stem 28 between the guide and support 30 and a nut 32 carried by the stem. The 75 guide and support 30 is of skeleton formation, and is secured to the valve plate 24 and extends through the opening 9 into the cylinder 1. A dome 33 is secured over the valve 27 by the cap screws 25, and is adapted 80 to protect the valve from dust and other foreign matter. The dome 33 is provided with a nipple 34 to permit the connection thereto of a pipe by which the exhaust can be carried at any desired distance from the 85 trap.

90 The trap shown in Figure 1 is adapted

for use in connection with a single cylinder hydro-carbon engine, and to permit it to be connected to a suitable support the head plates 4 and 6 are provided with lugs 35 arranged at right angles with respect thereto and apertured for the passage of lag screws 36 or other suitable attaching elements. While the trap is shown as adapted to be supported in a horizontal position, it is to be understood that it may be supported in a vertical position and provided with a blow out pipe as suggested by the hereinbefore identified patent. When the trap is supported in a vertical position, the attaching lugs 35 are omitted.

As shown in Figure 4 two or more of the traps may be assembled and connected together for use in connection with multiple cylinder hydro-carbon engines, and the assembled traps may be supported in a horizontal or vertical position. When two or more of the traps are to be used together, the head plates 4 and 6 are omitted, and in place thereof are employed head plates 4^a and 6^a of sufficient size to cover the ends of the assembled cylinders 1. The dome 33 is also omitted, and in lieu thereof an exhaust manifold 37 provided with a discharge port 38 is employed. The head plate 4^a is secured to the flanges 2 by rivets 5^a, and the head plate 6^a and exhaust manifold 37 are secured to the flanges 3 by bolts 7^a. The exhaust manifold 37 extends over the valves 27, and the exhaust from the cylinders 1 passes through the openings 9 into the manifold. As shown in Figures 5 and 6, the respective units of the multiple trap are adapted to be connected to the respective exhaust ports 38 of a multiple cylinder hydro-carbon engine 39 by tubes 40 and chambers 41. The chambers 41 are provided with hollow extensions 42 which enter the exhaust ports 39, and said chambers are secured in place by clamps 43. The tubes 40 are connected to the intake tubes 10 by couplings 44 and to the chambers 41 out of alignment with the exhaust ports 38 by couplings 45. The head plates 4^a and 6^a are provided with lugs 46 to permit the trap to be supported in advance of the cooling fan 47 so as to cause the rapid cooling of the exhaust for the purpose hereinbefore set forth. If desired the chambers 41 may be cast together or made separately as shown in the drawings.

From the foregoing description, taken in connection with the accompanying drawings, the advantages of the construction and of the method of operation of the exhaust trap will be readily apparent to those skilled in the art to which the same appertains. While I have described the principle of operation of the exhaust trap, together with the structure which I now consider to be the best embodiment thereof, I desire to have it understood that the structure shown is merely illustrative, and that such changes may be made when desired as are within the scope of the invention as claimed.

What is claimed is:—

1. An exhaust trap comprising a cylinder provided at its ends with outwardly directed flanges, first and second head plates secured to the flanges and the first head plate having a discharge port, an imperforate baffle tube of uniform diameter throughout and arranged within the cylinder with its ends spaced from the head plates, the end of the baffle tube adjacent the first head plate being closed and the end adjacent the second head plate being fully open, a conical baffle plate provided with openings and extending from the open end of the baffle tube in the direction of the second head plate and cylinder and terminating short of the second head plate, a cylindrical attaching flange extending from the conical baffle plate to the second head plate and contacting with the inner side of the cylinder, attaching elements engaging the cylinder and flange, and an exhaust tube secured to and extending inwardly and outwardly beyond the second head plate and extending into the baffle tube with its discharge end arranged in close proximity to the closed end of the baffle tube.

2. An exhaust trap comprising a pair of relatively spaced plates, a plurality of cylinders secured in relatively spaced relation to and between said plates, the plates constituting supports for the cylinders and closures for the ends thereof, baffle tubes within the cylinders, and exhaust tubes supported by one of said plates and discharging into the baffle tubes, and the other of said plates having openings constituting exhaust ports for the cylinders.

In testimony whereof I affix my signature.

ARTHUR J. CULP.
